UNITED STATES PATENT OFFICE.

JOHN E. POTTER, OF HILLSBORO, ILLINOIS.

COLLAPSIBLE BOX.

1,003,150.

Specification of Letters Patent. Patented Sept. 12, 1911.

Application filed July 30, 1909. Serial No. 516,425.

To all whom it may concern:

Be it known that I, JOHN E. POTTER, a citizen of the United States, residing at Hillsboro, in the county of Montgomery and State of Illinois, have invented a new and useful Improvement in Collapsible Boxes, of which the following is a specification.

This invention relates more particularly to improvements in collapsible boxes which are formed from a single sheet or blank of paper, card-board or other suitable material, by folding the parts thereof into position to form the box.

One object of this invention is to provide a strong, stiff box of this character, all the parts of which, including the cover, can be readily and economically formed from a single rectangular blank or sheet without any waste or loss of material and in which comparatively few cuts or incisions are made in the blank for folding the same, thereby greatly increasing the strength and stiffness of the box.

A further object of the invention is to so construct the box that when it is filled and the cover closed all the parts thereof are retained in their respective folded positions, and it is not necessary to use glue or other securing means for fastening the parts together to hold them in place.

In the accompanying drawings: Figure 1 is a plan view of the sheet or blank from which the box embodying the invention is formed. Fig. 2 is a perspective view of the blank showing the parts thereof partially folded. Fig. 3 is a perspective view of the box with the cover open. Fig. 4 is a similar view of the box with the cover partially closed, a portion of the cover being broken away to show its engagement with the ends of the box. Fig. 5 is a similar view of the box with the cover closed. Fig. 6 is a horizontal section of the box. Fig. 7 is a perspective view of a box of modified construction.

Like reference characters refer to like parts in the several figures.

A represents the rectangular blank or sheet of paper or other suitable material from which the box is formed. This blank is scored or creased along the dotted lines shown in Fig. 1, to facilitate the folding and to form a bottom portion b, side portions c c, end portions d d, and cover portions e e which are extensions of the side

portions c c. The blank is scored diagonally in the corners between the sides c c and the ends d d to form the triangular corner portions f f. The cover portions e e are each provided with end flaps e' e' which are separated from the triangular corner portions f by slits or incisions g in the opposite sides of the blank. This permits the triangular corners to be folded independently of the cover portions.

The blank A has straight edges without any projecting tongues or flaps and without any curved or angular portions cut away, the only cuts or incisions being the slits g between the end flaps of the cover portions and the triangular corners. The blank can thus be readily stamped or cut from a sheet of material and there is no waste of material whatever in cutting several blanks from a larger sheet, as would be the case if the blanks were of irregular shape or had projecting tongues or flaps. The only cuts or incisions in the blank are the slits g, and there are no cuts or incisions of any kind between the bottom, side and end portions of the blank which form the body of the box. This absence of cuts or incisions between the parts forming the body of the box adds greatly to the strength and stiffness of the box.

In folding the blank to form the box the side and end portions are bent up at right angles to the bottom to form the side and end walls of the box, the triangular corner portions being folded inwardly against the end walls of the box with their ends overlapping each other, as shown in Fig. 3. This forms the body portion of the box. The box is closed by folding the cover portions e e over the same, the end flaps e' e' being inserted between the triangular folded corners f and the end walls of the box, as shown in Figs. 4 and 6. The end flaps extend below the folded corners to the bottom of the box and cover the end walls thereof. The pressure of the contents of the box upon the folded corners and upon those portions of the end flaps which extend below the folded corners serves to bind the end flaps firmly between the folded corners and the end walls and against the latter, thereby securing the cover in its closed position on the box. The end flaps hold the folded corner portions f at each corner of the box from unfolding and thus lock the side and end walls of the box in their folded position and prevent the

same from separating or spreading apart. All of the parts of the box are securely held together when the cover has been closed and no glue or other securing or fastening means is required for this purpose. The box can thus be formed from the blank with ease and rapidity.

If desired, the overlapping ends of the folded corners may be fastened together, but for ordinary purposes this is not necessary, as the cover flaps, which are held in position by the pressure of the contents of the box, will securely lock the parts of the body together.

In the modified construction shown in Fig. 7, the cover h is formed in one piece and integral with one side of the box. It is provided with end flaps h' by which it is retained in engagement with the body portion of the box when closed, and has a side or front flap h^2 which is adapted to extend into the box along the inner side of the front wall for closing the front edge of the cover. The end flaps are held in place by the contents of the box and the end and front flaps interlock with the folded corners to hold the side and end walls in position to form the body of the box in the same manner as in the construction first described.

I claim as my invention:

1. A collapsible box consisting of a blank folded to form the end and side walls of the body of the box and unbroken folded corner portions which connect the end and side walls and extend into the box from the corners thereof adjacent to the end walls, and cover portions which project toward each

other from the opposite side walls of the box to form a cover therefor, both of said cover portions having end flaps which are adapted to enter between said folded corner portions and the end walls of the box for positively holding the walls of the box together and holding said cover portions in their closed positions, substantially as set forth.

2. A collapsible box consisting of a rectangular blank folded to form the end and side walls of the body of the box and unbroken folded corner portions which connect the end and side walls and extend into the box from the corners thereof adjacent to the side walls, said corner portions forming pockets with said end walls, and cover portions projecting toward each other from the opposite side walls of the box, said blanks having slits in the opposite end portions thereof which separate the corner portions from adjacent portions of the blank to form rectangular end flaps on the cover portions, all of said slits being parallel with the top edges of said side walls, said flaps being adapted to enter into the pockets between said folded corner portions and the end walls of the box for positively holding the walls of the box together and holding said cover portions in their closed positions, substantially as set forth.

Witness my hand, this 22nd day of July, 1909.

JOHN E. POTTER.
